UNITED STATES PATENT OFFICE.

OSCAR HERMANSON, OF NEW YORK, N. Y.

AIRSHIP.

1,191,077.

Specification of Letters Patent. Patented July 11, 1916.

Application filed August 20, 1915. Serial No. 46,551.

To all whom it may concern:

Be it known that I, OSCAR HERMANSON, a citizen of the United States, and resident of the borough of Manhattan, in the city, the county, and the State of New York, have invented new and useful Improvements on Airships, of which the following is a specification.

Experience with dirigible balloons has taught that such must have a structure resisting change of shape, because otherwise they become distorted and are broken in a gale, but production of such rigid airships so far has been very expensive and takes a long time, besides the large weight of the material which reduces the useful load to be carried.

The object of my present invention is an airship that at considerably smaller cost can be fast built with a reduced weight and if so desired, shall be so built that it can be taken apart for transportation and can be reassembled for service with small trouble in a short time, and I attain this object by means of a peculiar construction I have contrived, that comprises a skeleton of a small number of compression members, held together with steel rope of which the tensile strength can be fully utilized in producing a compact and powerful body.

In the accompanying drawing Figure 1 shows the frame of the airship and Figs. 2, 3, and 4 details of construction. Fig. 5 is the outer appearance of the ship and Fig. 6 a cross section of the same, while Fig. 7 refers to a special detail.

As shown in Fig. 1, the frame consists of a number of similar octagonal transverse frames, like that shown in Fig. 2, each consisting of two horizontal beams AD and HE, and two vertical beams BG and CF, which are joined at the crossings, I, K, L, and M, and at their ends tied with steel rope in the circumference ABCDEFGH. The size and number of these similar octagonal transverse frames varies according to the size and outer shape of the airship which will depend on the weight it shall carry, and on the speed with which it shall travel. Of course, I do not confine myself to this peculiar octagonal shape of transverse frames, but may use some other pattern if there is special occasion for, but I prefer the afore defined octagon because I have found that

thereby the material in the compression members is reduced to a minimum.

The several transverse frames are joined in the center by the longitudinal beams II, KK, LL, and MM, and at the circumference by steel cable AA, BB, CC, DD, EE, FF, GG, and HH. Thus the whole frame consists mostly of steel rope with a small complement of rigid members, and since the high tensile strength of the steel wire can be taxed to its limit, this construction affords a large saving of material, compared with other designs, and renders the structure lighter and cheaper. Another advantage of this peculiar frame is that strains and stresses in all of its members can be calculated exactly as in a bridge truss when the lifting power of the gas to be used becomes known and the load to be carried has been located.

Estimating the strains and stresses for all the members of the frame in its normal position, we find for every transverse frame the maxima stresses in its 12 compression members and the maxima strains in its 8 tension members; and so we find the maxima stresses in the 4 compression members II, KK, LL, and MM, between any two adjacent transverse frames and the maxima strains in the 8 tension members AA, BB, CC, DD, EE, FF, GG, and HH. Considering now that in a tempest the ship is liable to roll over sidewise and even to turn upside down, whereby the afore said stresses and strains in the single members are shifting around in a circle, we see that all of the homologous members must receive the same maximum strength. This means, in every transverse frame its 8 peripheral struts A1, B1, C1, D1, E1, F1, G1, and H1, must be of equal strength, and the 4 central struts I1, K1, L1, and M1, again must be of equal strength, and so the 8 tension members AB, BC, CD, DE, EF, FG, and GH, must receive the same strength. Similarly we find for each space between two adjacent transverse frames that the 4 longitudinal struts II, KK, LL, and MM, must be of the same strength, and the 8 tension members AA, BB, CC, DD, EE, FF, GG, and HH, also must be of equal strength.

It is apparent that in any other kind of frame the strains and stresses of all the members under the considered variations

cannot be calculated with the same exactitude, if calculated they can be at all, and leaving it to guess work, either excessive safety factors must be introduced, thereby increasing the weight of the structure, or an unreliable makeshift will result.

Estimating strength of material in the above indicated manner for larger airships the future might demand, structural steel of the proper shape and size will be available, but for lighter ships demanded by present belligerents, I prefer to use steel tubing for all the struts, for sake of convenience. Using commercial tubing, I merely order cut lengths, and have rigging pins for the end struts made, such as shown in Fig. 3. This pin 1 fits into the tube 2, to which it is secured by the bolt 3, and provides hold for cables around its neck 4. The central connection of the struts, of which 6 meet in every one of the 4 joints I, K, L, and M, is obtained by means of a six armed cross, shown in Fig. 4. These crosses may be forged or may be cast in one piece and then turned on a lathe, so as to offer an exact fit to each of the joining 6 tubes which will be secured to the cross by means of bolts as in the former case. If these bolts are screwed, they readily can be removed and the whole frame taken apart, and if the crosses and the tubes are properly marked to indicate where every piece belongs, the dismounted structure may be shipped anywhere and reassembled without confusion.

In Fig. 1 also has been shown the horizontal rudder 5, and the vertical rudder 6, rigged in position to the frame. In order to prevent twisting of the ship around its longitudinal axis, diagonal rigging with light rope will be added between adjacent transverse frames, which I have omitted in the drawing for the sake of transparency.

In Fig. 5 the airship is shown as it will look from the outside after the frame of Fig. 4 has been covered. The cover may be made of sheet metal or of sail cloth that has been water proofed and fire proofed, which can be accomplished by the same process, and it may be made in one piece, or in removable sections, laced to one another, or to the frame. Within the cover, between every couple of transverse adjacent frames, lifting gas bags are placed, and if we prefer a single bag for every interstice, it may be made of octagonal shape, exactly fitting in to fill the space. The material for these bags must be gas proof and the four tubes I, K, L, and M, perforating each bag, must be cemented or mechanically secured to the bag in a gas tight seal.

In order to provide for the expansion of the gas, only so much gas is blown into each bag as will inflate it completely at its fullest expansion. In this manner the bags normally will not fill the whole space between

the transverse frames, but lifted by the lighter gas, they will cling tightly to the outer protecting cover on top and at the sides, while at the bottom the inflated bag will float on air, sinking and rising as the difference of pressures changes.

Accommodations for crew and passengers, for machinery, armament, fuel and other stores, could be provided in gondolas or nacelles, hitched somewhere to the frame of the airship, but similar attachments impede the mobility of the ship, therefore I prefer to locate all such accommodations inside the outer cover of the ship, where they will occupy but an insignificant fraction of the available space and readily can be so located as not to interfere with the functions of the ship.

In order to rid the airship of embarrassment resulting from the varying buoyancy of the lifting gas I prefer to load the ship so that it always remains a little heavier than the air it displaces and consequently will sink and stick to the ground when not moving. When in motion its propelling power will easily raise the ship to any level, since no power is required to support the moving ship. The lifting effect of its propelling power may be increased by providing the ship with wings, which in Fig. 5 are suggested in the shape of biplanes 7, laterally protruding from its body. As shown in cross section by the diagram Fig. 6, these biplanes are obtained by an extension of the horizontal beams in one or more of the transverse frames, which extension furnishes on each side two parallel wings that are trussed in the manner of a biplane and provide operating platforms, on which the propelling machinery may be mounted, as indicated by the diagram.

This airship may be mounted on wheels or may alight on water. If such an airship is to do service above the ocean where it might be compelled to alight on turbulent water, it will be damaged without efficient protection, but this protection I obtain by means of an inflated bottom. The line HH in Fig. 5 marks the upper rim of the lower section of the shell. If this portion of the bottom is airtight and water tight, we may cover the bottom with another air tight and water tight skin that is free from the original bottom and only at the border HH, EE is air tight joined to it, forming with a sealed envelop that covers the bottom of the ship. If we inflate this envelop with air, it will somewhat expand and form an air-cushion around the bottom, while the other side, forming the original cover of the bottom, will bulge out inward in segments in a manner suggested by Fig. 7, where the shaded portion is a cross section through the air-cushion protecting the bottom of the ship. With such a protected bottom it

safely can alight on waves and rise again, so that such an airship will be most valuable in the life saving service for approaching sinking ships.

5 In order to protect the propellers of such a ship, that are shown in Fig. 6, I provide the operating platform 8 with floats 9 underneath the propellers which will prevent the latter from touching the water. These 10 floats may be spherical or of any other convenient shape. As shown in the diagram, they are supposed to consist of hemispherical buckets 10, provided with pliable air-tight hemispherical lids 11 that will 15 stand out as shown in the diagram when inflated with air, but when the air is withdrawn by means of a pump, they will fold in touching the outer cups as a lining. The 20 purpose of this device is to serve either as a lifting air-cushion, when inflated, or as a mooring weight, when deflated and filling with water. These floats are only to be used 25 on the water; when in the air they shall not increase the resistance to the moving ship and therefore are pulled up with the stanchions 12 that hinge at the platform 8 and turn in as shown in Fig. 5.

Having described in the foregoing my invention, what I claim as new and desire to 30 secure by Letters Patent, is:

1. An airship skeleton consisting of a number of similar octagonal transverse frames, each formed of two pairs of crossed beams, that at the four crossings are braced 35 by four longitudinal beams joining adjacent transverse frames; and of wire connect-

ing peripherally the corners of each frame, and longitudinally the corners of adjacent frames.

2. In a skeleton frame, built of tubes, connections therefor at their meeting points comprising an easily removable cross carrying a plurality of arms, fitting into the joining tubes and provided at their bases with facets for the tubes to rest upon. 40

3. In a skeleton frame, built of tubes, easily removable rigging pins at the free ends of these tubes, that fit in the tubes and carry heads for fastening the rigging cables, and facets for the tubes to rest upon. 45

4. A protecting float of which the shell consists of one less and one more pliable half, so that when inflated with air, the shell acts as a float, but when the air filling the shell is withdrawn by means of a pump, the more pliable half of the shell folds in, forming a lining for the other half, and the whole filling with water acts as a mooring bucket. 55

5. Around the bottom of a floating ship 60 an airtight and watertight pliable envelop, at its rim tightly fastened to the bottom of the ship, so that when this envelop is inflated with air, it forms a protecting air-cushion around the bottom of the ship. 65

In testimony whereof I have signed my name to this specification in the presence of two subscribing witnesses.

OSCAR HERMANSON.
